UNITED STATES PATENT OFFICE.

ALBERT HOMER PORTER, OF PUEBLO, COLORADO.

AUTOMATIC STIRRUP.

1,323,549.

Specification of Letters Patent.

Patented Dec. 2, 1919.

Application filed May 22, 1919. Serial No. 298,899.

To all whom it may concern:

Be it known that I, ALBERT H. PORTER, a citizen of the United States, residing at Pueblo, in the county of Pueblo and State 5 of Colorado, have invented certain new and useful Improvements in Automatic Stirrups, of which the following is a specification.

This invention relates to riding stirrups and more particularly to an improved construction having tripping means by which the operator may quickly release the stirrup from the stirrup strap if it should become necessary to quickly release the same.

The primary object of the invention is to 15 provide a stirrup of this character which will have a tripping arrangement designed to be readily engaged by the foot of the person driving the animal whereby the device will be quickly unlocked or detached 20 when required.

A further object of the invention is to provide a device of this character which consists of comparatively few parts and is simple in construction but durable and well 25 adapted to withstand the rough usage to which devices of this character are ordinarily subjected.

For a full description of the invention and the advantages and merits thereof, reference 30 is to be had to the following description and accompanying drawings, in which:—

Figure 1 is an edge elevation of the device constructed in accordance with my invention,

Fig. 2 is a side elevation of the same partly broken away to show some of the parts in section,

Fig. 3 is a fragmentary side elevation partly in section.

Referring to the drawings, wherein is illustrated the preferred form of my invention, in which like characters of reference indicate like or corresponding parts throughout the several views, the stirrup 1 is U-shaped in the usual manner and includes the parallel arms 2 each of which has its upper free end provided with a slot 3. The trunnions 4 of a roller 5 are received in the slot 3 and the stirrup straps 6 are connected 45 to the roller 5 whereby the stirrup is suspended in the usual manner.

In order that the trunnions 4 may be maintained in position in the slots 3, I have provided the latches 7. The latches are 55 formed of a single piece of wire of suitable gage which has its intermediate portion

straight to form the guard 8 and this guard member extends across the space between the parallel arms 2 and terminates in side arms 9 which lie parallel with the arms 2. 60 As shown to advantage in Fig. 1 each side arm 9 is normally spaced away from the stirrup and a coil spring 10 is interposed between each arm 9 and a stop member 11. An offset portion 12 connected to each arm 65 9 maintains the arm 9 in the outwardly spaced position as shown in Fig. 1 and each portion 12 is provided with a loop 13 adapted to receive a pivot member 14 whereby the tripping device will be pivotally 70 mounted on the stirrup. The locking hook 15 extends from the loop 14 and is adapted to pass over the corresponding trunnions 4 and the terminal of the hook is adapted to engage and disengage an eyelet 16 conveniently located on the upper end of the arm 2, as shown to advantage in Figs. 1 and 2 whereby bending or twisting of the hook will be prevented when a pressure is 75 exerted on the stirrup.

Obviously the hook members when engaged in the position shown will maintain their engagement with the eyelets 16 and consequently the trunnions 4 will be maintained in position against displacement from 80 the slots 3. The spring 10 acts to maintain the hooks in the position stated. When the operator desires to release the hooks it is merely necessary to actuate the guard member 8 whereupon the arms 9 will swing on 85 the pivot member and cause the hooks to disengage the eyelets 16, and permit the trunnions 4 to be dislodged from the slot 3.

The foregoing description and accompanying drawings have reference to what 90 might be considered to be the approved or preferred form of my invention. I desire it to be understood that I may make such changes in the construction, combination and arrangement of parts, materials, dimensions, et cetera, as may prove expedient and fall within the scope of the appended claim.

Having thus fully described my invention what I claim as new and desire to secure by Letters Patent, is:—

A stirrup having parallel side arms each provided with a slot in the upper end, a roller having trunnions adapted to be received in the slots, eyes secured to the side arms adjacent one edge of the slot, a guard member pivotally connected to the side arms, said guard member comprising a straight

portion extending across the space between the side arms, vertically extending portions extending parallel with the side arms and hooks formed on the ends of said vertical 5 extending portions, said hooks adapted to extend over the trunnions of the rollers and having their ends received in the eyes, and springs secured to the side arms and en-

gaging the vertical portions of the guard for normally holding the hooks in the eyes. 10

In testimony whereof I affix my signature in presence of two witnesses.

ALBERT HOMER PORTER.
